BUFFER AND DRAFT GEAR

John E. Graham, Huntington, W. Va., assignor to
The Watt Car & Wheel Company, Barnesville,
Ohio, a corporation of Ohio

Application October 10, 1945, Serial No. 621,526

12 Claims. (Cl. 213—9)

1

My invention relates to improvements in buffer and draft gear and has to do, more particularly, with improvements in a buffer and draft gear that is especially suitable for use on mine cars.

The principal object of my invention is to provide a buffer and draft gear, which is especially suitable for use on a mine car, and which, though of strong and sturdy construction, is comparatively simple and economical to manufacture and assemble.

A further object of my invention is to provide a buffer and draft gear for mine cars, of such nature that the parts thereof may be readily assembled in operative relation upon the end sill of the mine car.

Another object of my invention is to provide a buffer and draft gear construction, of such nature that the parts may be readily disassembled, without the use of special tools or skills, in case the repair or replacement of any part becomes necessary.

Further objects, and objects relating to details of construction and economies of operation, will definitely appear from the detailed description to follow. In one instance, I have accomplished the objects of my invention by the devices and means described in the following specification. My invention is clearly defined and pointed out in the appended claims. A structure constituting a preferred embodiment of my invention is illustrated in the accompanying drawings, forming a part of this specification, in which:

Fig. 1 is a view in front elevation of a buffer and draft gear embodying my invention.

Fig. 2 is a bottom plan view of the buffer and draft gear.

Fig. 3 is a view in end elevation, taken on the line 3—3 of Fig. 1.

Fig. 4 is a horizontal sectional view through the buffer and draft gear, taken on the line 4—4 of Fig. 1.

Fig. 5 is a vertical, sectional view, taken on the line 5—5 of Fig. 1.

Fig. 6 is a view of the draft element in front elevation.

Fig. 7 is a bottom plan view of the draft element and

Fig. 8 is a view of the draft element in side elevation.

In the drawings, the same reference numerals refer to the same parts throughout the several views, and the sectional views are taken looking in the direction of the arrows at the ends of the section lines.

2

Referring to the numbered parts of the drawings, my improved buffer and draft gear is to be mounted on the end sill 10 of a mine car. A housing is secured to this end sill, which is made up of a pair of channels welded in endwise relationship to said end sill. The flanges 12 and 13 of these channels extend toward each other and form the top and bottom walls of the housing, but the channels are so spaced apart that the edges of said flanges are separated, thus forming openings in the top and bottom of the housing walls. The end sill 10 forms the rear wall of the housing, the bases 11 of the channels form the side walls of the housing, the top flanges 12 of the channels form the top wall of the housing, and the bottom flanges 13 of the channels form the bottom wall of the housing. The front end of this housing is open.

A draft element is slidably mounted within the housing and includes a flat plate 14, which is adapted to engage the front face of the sill 10 and the lower edge of which is slidably mounted on the flanges 13 forming the bottom wall of the housing. A pair of flanges 15 are secured to the plate 14, in edgewise relationship, and extend forwardly therefrom in vertically spaced relationship. These flanges, as shown in Fig. 6, extend the full length of the plate 14. A pair of horizontally spaced brackets 16 are applied to the upper edge of the plate 14 and to the uppermost flange 15 and secured thereto, each bracket having a shoulder 17 adapted to engage the upper corner of the plate 14. These brackets 16 extend upwardly through the opening in the top wall of the housing, formed by the spacing of flanges 12. A hitching arm 18 is applied to and welded to the upper ends of the brackets 16, and is arranged centrally of the structure, and said hitching arm extends forwardly parallel to the top wall of the housing. This arm 18 has a hole 19 therein, adapted to receive a coupling pin. It is spaced from the top wall of the housing sufficiently to receive a coupling link between said top wall and said hitching arm. Straps 20 are fastened to the flanges 15 and extend forwardly therefrom, said straps being arranged centrally of the structure. The forward portions of these straps are bent toward each other, at 21, and the foremost portions of the straps are secured together to form a hitching tongue 22, which lies in the horizontal plane midway between the flanges 15. This hitching tongue has a hole 23 therein, in line with the hole 19 of the hitching arm, and adapted to receive the lower end of the coupling pin.

A buffer element is slidably mounted in the

housing and projects from the open front end thereof, and this buffer element comprises a convex front face 24 and the upper and lower rearwardly-extending flanges 25. It is to be noted that this buffer element is substantially a channel member, of which the front face 24 constitutes the base. Plates 26 are mounted within this channel member, adjacent the ends thereof, and rigidly secured thereto, and said plates 26 extend rearwardly beyond the rear edges of flanges 25. These rearwardly-extending portions of the plates have elongated, rectangular slots 27 therein. The buffer element is slidably mounted on the bottom wall of the housing, its lower flange 25 being in engagement with and supported thereby, and the plates 26 extend rearwardly parallel to the side walls 11 of the housing. When the parts are assembled, the hitching tongue 22 extends into the buffer element, midway between the top and bottom flanges 25 thereof. Elongated slots 28 are provided in the top and bottom flanges 25 of the buffer element, to permit the passage of the coupling pin.

Pads 29 are secured to the inner surface of the front face 24 of the buffer element, and support rings 30, which enter the front ends of compression springs 31, arranged one on either side of the hitching tongue 22 and interposed between the pads 29 and the front edges of the flanges 15. A square locking bar 33, having a head 34, extends through square holes 32 in the side walls 11 of the housing, through the slots 27 in the plates 26 of the buffer element, and in front of the plate 14 and between the flanges 15 of said draft element. The washer 35 is applied between the head 34 of the locking bar and the adjacent side wall 11 of the housing, and another washer 35 is applied on the other end of the locking bar, engaging the side wall 11 and being held in position by a cotter pin passed through the hole 36 in the projecting end of said bar. When the parts are in the relative positions shown in Fig. 5, the forward face of the locking bar 33 is in line with the forward edges of flanges 15 and, under such circumstances, the rear ends of the compression springs 31 seat on the front face of the locking bar, as well as on the front edges of said flanges.

The operation of this buffer and draft gear should be quite apparent from the foregoing description, but I will describe it briefly, at this point. When the apparatus is in buff, pressure is applied to the face 24 of the buffer element acting rearwardly, that is, in the direction of the end sill 10. Rearward movement of the draft element is limited by engagement of the plate 14 with the front face of the end sill, so that the front edges of the flanges 15 form seats, against which the springs 31 are compressed by rearward movement of the buffer element, which rearward movement is limited to that permitted by the engagement of the locking bar 33, fixed to the housing, in the elongated slots 27 of plates 26 of the buffer element. A pull on a coupling link, located between the hitching arm 18 and the top wall 12 of the housing and through which a coupling pin received in the holes 19 and 23 passes, applies draft to the draft element, which tends to move it forwardly in the housing, that is, away from the end sill 10. This tends to move the buffer element 24 outwardly in the housing, but such outward movement of the buffer element is limited by the engagement of the rear ends of slots 27 with the rear face of the locking bar 33, so that the springs 31 yieldingly oppose this draft movement of the draft element. Forward movement of the draft

element is limited by the engagement of the front face of plate 14 with the rear face of locking bar 33.

The parts of this buffer and draft gear can be conveniently and economically made, and assembled upon a finished mine car. The housing is made and fastened to the end sill by welding the channel members, having the bases 11, in endwise relation on said end sill. The draft element can then be inserted in position within this housing. The compression springs can then be inserted with their rear ends seated on the forward edges of flanges 15, and, then, the buffer element can be slid into position in the housing, with the rings 30 centered in the forward ends of the springs 31, and temporarily held in such position that the slots 27 are in line with the holes 32 in the side walls of the housing. The locking bar 33 can then be inserted and this holds the parts together. The parts can be quickly disassembled by removing the cotter pin from hole 36 and driving out the locking bar 33, the removal of which permits the parts of this buffer and draft gear to be removed.

I am aware that the particular buffer and draft gear construction illustrated herein is susceptible of considerable variation without departing from the spirit of my invention and, therefore, I claim my invention broadly, as indicated by the appended claims.

Having thus described my invention, what I claim as new and useful, and desire to secure by Letters Patent, is:

1. A buffer and draft gear comprising the combination with the end sill of a car, of a housing secured to and extending forwardly from said end sill, and having an open front end; a draft element slidably mounted in said housing, in front of said end sill; a buffer element slidably mounted in said housing, and projecting from the open front end thereof, said buffer element having side walls with elongated openings therein; compression springs interposed between said draft element and said buffer element and tending to project said buffer element from said housing; and a longitudinally removable locking bar carried by said housing, and extending transversely to the line of draft and parallel to said end sill at a fixed distance therefrom, said bar passing through said elongated openings in the buffer side walls, and in front of said draft element, and serving to limit movement of said buffer element under both buff and draft and movement of said draft element under draft, movement of the latter under buff being limited by its engagement with said end sill.

2. A buffer and draft gear comprising the combination with the end sill of a car, of a housing secured to and extending forwardly from said end sill, and having an open front end; a draft element slidably mounted in said housing, in front of said end sill; a buffer element slidably mounted in said housing, and projecting from the open front end thereof, said buffer element including a channel member having a longitudinally-curved base constituting the convex front end of the buffer element, and rearwardly extending flanges forming the top and bottom walls of said buffer element, and plates secured in said channel at the ends thereof and extending rearwardly therefrom to form the side walls of said buffer element, said plates having aligned, elongated openings therein; compression springs interposed between said draft element and the base of said buffer channel and tending to project said buffer element

from said housing; and a longitudinally removable locking bar carried by said housing, and extending transversely to the line of draft and parallel to said end sill at a fixed distance therefrom, said bar passing through said elongated openings in the plates of said buffer element and in front of said draft element, and serving to limit movement of said buffer element under both buff and draft and movement of said draft element under draft, movement of the latter under buff being limited by its engagement with said end sill.

3. A buffer and draft gear comprising the combination with the end sill of a car, of a pair of channel members secured to said end sill in end-wise relation thereto, said channel members being spaced apart on opposite sides of the line of draft, with their flanges extending toward each other and their uppermost flanges spaced apart to provide an opening therebetween, said channel members and end sill forming a housing, the rear wall of which is said end sill, the side walls of which are the bases of said channel members, and the top and bottom walls of which are the flanges of said channels; a draft element slidably mounted in said housing in front of said end sill, and having a hitching portion extending through the opening provided by the spacing of said flanges; a buffer element slidably mounted in said housing, and projecting from the open front end thereof, said buffer element having side walls with elongated openings therein; compression springs interposed between said draft element and said buffer element and tending to project said buffer element from said housing; and a longitudinally removable locking bar carried by said housing, and extending transversely to the line of draft and parallel to said end sill at a fixed distance therefrom, said bar passing through openings in the bases of said channels, through said elongated openings in the buffer side walls, and in front of said draft element, and serving to limit movement of said buffer element under both buff and draft and movement of said draft element under draft, movement of the latter under buff being limited by its engagement with said end sill.

4. A buffer and draft gear comprising the combination with the end sill of a car, of a housing secured to and extending forwardly from said end sill, and having an open front end and a top wall with a longitudinally-extending opening therein; a draft element slidably mounted on the bottom wall of said housing in front of said end sill, and having a hitching portion extending upwardly through said opening in the top wall of said housing and forwardly in spaced relation to and parallel to said top wall; a buffer element slidably mounted on the bottom wall of said housing and projecting from the open front end thereof, said buffer element having spaced, rearwardly-extending portions provided with elongated openings therein; compression springs interposed between said draft element and said buffer element and tending to project the latter from said housing; and a longitudinally removable locking bar carried by said housing, and extending transversely to the line of draft and parallel to said end sill at a fixed distance therefrom, said bar passing through said elongated openings in the buffer element and in front of said draft element, and serving to limit movement of said buffer element under both buff and draft and movement of said draft element under draft, movement of the latter under buff being limited by its engagement with said end sill.

5. A buffer and draft gear comprising the combination with the end sill of a car, of a housing secured to and extending forwardly from said end sill, and having top and bottom walls and an open front end, said top wall having a longitudinally-extending opening centrally thereof; a draft element including a flat plate adapted to engage said end sill, and with its lower edge slideable on the bottom wall of said housing, and a hitching portion secured to said plate and extending upwardly therefrom through the opening in the top wall of said housing; a buffer element slidably mounted on the bottom wall of said housing, and projecting from the open front end thereof, said buffer element having spaced rearwardly-extending portions provided with aligned elongated openings; compression springs interposed between said draft element and said buffer element and tending to project said buffer element from said housing; and a longitudinally removable locking bar carried by said housing, and extending transversely of the line of draft and parallel to said end sill at a fixed distance therefrom, said bar passing through said elongated openings in the buffer element and in front of said plate of said draft element, and serving to limit movement of said buffer element under both buff and draft and movement of said draft element under draft, movement of the latter under buff being limited by the engagement of said plate with said end sill.

6. A buffer and draft gear comprising the combination with the end sill of a car, of a housing secured to and extending forwardly from said end sill and having an open front end; a draft element slidably mounted in said housing in front of said sill and including a flat plate adapted to engage said end sill, and a pair of spaced flanges secured in edgewise relation to said plate and extending forwardly therefrom; a buffer element slidably mounted in said housing and projecting from the open front end thereof, said buffer element having spaced rearwardly-extending portions provided with aligned elongated openings therein; compression springs interposed between said flanges of said draft element and said buffer element and tending to project said buffer element from said housing; and a longitudinally removable locking bar carried by said housing, and extending transversely to the line of draft and parallel to said end sill at a fixed distance therefrom, said bar passing through said elongated openings in the buffer element, and in front of said plate and between said flanges of the draft element, and serving to limit movement of said buffer element under both buff and draft and movement of said draft element under draft, movement of the latter under buff being limited by the engagement of said plate with said end sill.

7. A buffer and draft gear comprising the combination with the end sill of a car, of a housing secured to and extending forwardly from said end sill and having an open front end, a bottom wall and a top wall having a longitudinally-extending central opening therein; a draft element including a flat plate adapted to engage said end sill and having its lower edge slideable upon the bottom wall of said housing, a pair of flanges secured to the front face of said plate in edgewise relation and extending forwardly therefrom, and a hitching portion secured to the upper portion of said plate and the uppermost of said flanges and extending upwardly through the opening in said top wall and forwardly parallel to said top

wall; a buffer element slidably mounted on the bottom wall of said housing and projecting from the open front end thereof, said buffer element having spaced portions extending rearwardly and provided with aligned elongated openings; compression springs interposed between said buffer element and the front edges of said flanges and tending to project said buffer element from said housing; and a longitudinally removable locking bar carried by said housing and extending transversely to the line of draft and parallel to said end sill at a fixed distance therefrom, said bar passing through said elongated openings in the buffer element, and in front of the plate of said draft element and between said flanges, and serving to limit movement of said buffer element under both buff and draft and movement of said draft element under draft, movement of the latter under buff being limited by the engagement of said plate with said end sill.

8. A buffer and draft gear comprising the combination with the end sill of a car, of a housing secured to and extending forwardly from said end sill and having an open front end, a bottom wall and a top wall provided with a longitudinally-extending central opening therein; a draft element including a flat plate adapted to engage said end sill and mounted in said housing with its lower edge slidable upon the bottom wall thereof, a pair of spaced flanges secured to said plate in edgewise relation and extending forwardly therefrom, a pair of brackets secured to the upper portion of said plate and the uppermost of said flanges and extending upwardly in spaced relation through the opening in the top wall of said housing, a hitching arm secured to said brackets and extending forwardly therefrom parallel to the top wall of said housing, said hitching arm having a hole therein adapted to receive a coupling pin, and a pair of straps secured to said flanges and extending forwardly therefrom, the forward portions of said straps being bent toward each other and secured together to form a hitching tongue lying midway between the top and bottom walls of the housing, said tongue having a hole therethrough in line with the hole in said hitching arm and adapted to receive a coupling pin; a buffer element slidably mounted in said housing and projecting from the open front end thereof, said buffer element having spaced portions extending rearwardly and provided with aligned elongated openings; compression springs, one on either side of the hitching tongue, interposed between the forward edges of said flanges and said buffer element, and tending to project said buffer element from said housing; and a longitudinally removable locking bar carried by said housing and extending transversely to the line of draft and parallel to said end sill at a fixed distance therefrom, said bar passing through said elongated openings in the buffer element and in front of said plate of the draft element and between said flanges, and serving to limit movement of said buffer element under both buff and draft and movement of said draft element under draft, movement of the latter under buff being limited by the engagement of said plate with said end sill.

9. A buffer and draft gear comprising the combination with the end sill of a car, of a housing secured to and extending forwardly from said end sill, and having an open front end; a draft element slidably mounted in said housing in front of said end sill, and including a flat plate adapted

to engage the front face of said end sill, and a pair of flanges secured in spaced, edgewise relation to said plate and extending forwardly therefrom; a buffer element slidably mounted in said housing and projecting from the open front end thereof; compression springs interposed between the front edges of said flanges and said buffer element and tending to project said buffer element from said housing; and a locking bar carried by said housing and cooperating with said buffer and draft elements to limit movement of the buffer element under both buff and draft and movement of the draft element under draft, movement of the latter under buff being limited by the engagement of said plate with said end sill.

10. A buffer and draft gear comprising the combination with the end sill of a car, of a housing secured to and extending forwardly from said end sill, and having an open front end, a bottom wall and a top wall provided with a longitudinally-extending, central opening therein; a draft element including a flat plate in front of said end sill, having its lower edge slidable on the bottom wall of said housing, a pair of flanges secured to said plate in spaced, edgewise relation and extending forwardly therefrom, and a hitching portion secured to said plate and the uppermost of said flanges, and extending upwardly through said opening in the top wall of said housing and forwardly parallel to said top wall; a buffer element slidably mounted on the bottom wall of said housing and projecting from the open front end thereof; compression springs interposed between the front edges of said flanges and said buffer element and tending to project said buffer element from said housing; and a locking bar carried by said housing and cooperating with said buffer and draft elements to limit movement of said buffer element under both buff and draft and movement of said draft element under draft, movement of the latter under buff being limited by engagement of said plate with said end sill.

11. A buffer and draft gear comprising the combination with the end sill of a car, of a housing secured to and extending forwardly from said end sill and having an open front end, a bottom wall and a top wall having a longitudinally-extending central opening therein; a draft element including a flat plate adapted to engage the front face of said end sill and having its lower edge slidable on the bottom wall of said housing, a pair of flanges secured to said plate in spaced, edgewise relation thereto and extending forwardly therefrom, a hitching arm secured to said plate and extending upwardly through said opening in the top wall of the housing and forwardly parallel to said front wall and provided with a hole adapted to receive a coupling pin, and a pair of straps secured to said flanges and extending forwardly therefrom, with their forward ends bent toward each other and secured together to form a hitching tongue extending midway between the top and bottom walls of said housing and having a hole therein in line with the hole in said hitching arm and adapted to receive the coupling pin; a buffer element slidably mounted on the bottom wall of said housing and projecting from the open front end thereof; compression springs, one on either side of said tongue, interposed between the front edges of said flanges and said buffer element and tending to project said buffer element from said housing; and a locking bar carried by said housing and cooperating with said buffer

and draft elements to limit movement of said buffer element under both buff and draft and movement of said draft element under draft, movement of the latter under buff being limited by engagement of said plate with said end sill.

12. A buffer and draft gear comprising the combination with the end sill of a car, of a housing secured to and extending forwardly from said end sill and having an open front end, a bottom wall and a top wall having a longitudinally-extending, central opening therein; a draft element including a flat plate adapted to engage the front face of said end sill and having its lower edge slidable on the bottom wall of said housing, a pair of flanges secured to said plate in spaced, edgewise relation and extending forwardly therefrom, a pair of brackets secured to said plate and the uppermost of said flanges and extending upwardly through the upper wall of said housing in spaced relation, a hitching arm secured to said brackets and extending forwardly parallel to the top wall of said housing, said arm

having a hole therein to receive a coupling pin, and a pair of straps secured to said flanges and extending forwardly therefrom, with their forward portions bent toward each other and secured together to form a hitching tongue provided with a hole in line with the hole in said hitching arm and adapted to receive the coupling pin; a buffer element slidably mounted on the bottom wall of said housing and projecting from the open front end thereof; compression springs, one on each side of said hitching tongue, interposed between the front edges of said flanges and said buffer element and tending to project said buffer element from said housing; and a locking bar carried by said housing and cooperating with said buffer and draft elements to limit movement of said buffer element under both buff and draft and movement of said draft element under draft, movement of the latter under buff being limited by engagement of said plate with said end sill.

JOHN E. GRAHAM.
